ARTHUR G. MCKEE, OF CLEVELAND, OHIO

METHOD AND APPARATUS FOR TREATING GASES

Application filed July 1, 1925. Serial No. 40,748.

This invention relates to methods of and apparatus for treating gases, such for example as gases from blast furnaces.

One object of the invention is to devise new and improved methods and apparatus for removing heat and foreign materials from gases efficiently and with the use of a relatively small amount of liquid as compared with the liquid required by previous methods and apparatus.

Another object is to construct apparatus for cleaning, scrubbing and cooling gases provided with spray devices so constructed and arranged that each device is readily accessible and may function as a unit independently of the remaining similar devices, particularly in such respects as speed of rotation, rate of pumping, and removability for repair or replacement.

A still further object is to construct gas scrubbing, cleaning and cooling apparatus including new parts and new and improved arrangements and combinations of parts by which new and improved advantages and results are obtained.

Prior to my invention a common method of scrubbing, cleaning and cooling gases, such as blast furnace gas and similar gaseous substances, included passing the gas to be cleaned and cooled through a scrubber where liquid spray in certain stages removed the solids and foreign materials from and initially cooled the gases, and then in other stages removed some remaining foreign materials and finally cooled the gases. A large part of the liquid used for final cooling and cleaning was discarded into the stream or other water source as it did not contain an objectionable amount of solid matter but substantially all the liquid which was used to remove the solids and do the initial cooling carried so much foreign matter that it necessarily was passed through settling tanks or thickening apparatus, which separated most of the liquid from the solids and left the solids in a condition suitable for filter-pressing, or some similar operation, where the remainder of the liquid could be removed. The separated liquid was either discharged into the water courses in a dirty and objectionable condi-

tion or was freed from all but a small amount, say about ten grains of solids or less per gallon of liquid, as required by law and was then returned to the stream. Large quantities of water were thus passed through the scrubber and thickening apparatus and then discarded, to clean which water to the required degree apparatus or settling tanks of correspondingly large size, or several devices of smaller sizes was required.

In contrast therewith, instead of discarding a large part of the liquid used for final cooling of the gases, I circulate such liquid through a cooler where it is deprived of the heat it obtained from the gases, and return the cooled liquid to the scrubber. Furthermore, instead of discarding to the water courses large quantities of liquid from which substantially all foreign material taken from the gases has been separated, I circulate the liquid carrying the foreign materials through thickening apparatus where the bulk of the solids is removed but leaving substantial amounts of solids, say from 100 to 200 grains per gallon or more. This liquid is returned to the scrubber where it unites with liquid therein and again acts to remove solids from gases. By my invention, therefore, I am enabled to remove the solid materials from and cool the same amount of gas substantially as heretofore but with a very much smaller amount of water and with all the practical advantages incident to this decreased amount.

Various apparatus for scrubbing, cleaning and cooling gases of the prior art have included a long, main drive shaft which carried a plurality of spray devices and actuated the latter all at the same speed. When any mechanical difficulties arose with any of the spray devices, the main shaft, or its bearings, the entire apparatus was affected. On the contrary my apparatus is so constructed that each spray device constitutes a unit which is independently supported and may be actuated at various speeds, or caused to pump various amounts of water, or to change the nature of the spray produced, is readily accessible for repairs, easily removable for replacement by a new unit and all without affecting the remainder of the apparatus.

In the drawings accompanying and forming a part of this specification:

Fig. 1 is a view, partly in section, of apparatus embodying my invention;

Fig. 2 is an enlarged, fragmentary detail view, partly in central vertical section of the apparatus of Fig. 1;

Fig. 3 is a top plan view taken on line 3—3 of Fig. 2 with the spray forming device removed;

Figs. 4 and 5 are sectional views taken respectively on lines 4—4 and 5—5 of Fig. 3;

Fig. 6 is a view similar to Fig. 2 but showing a modified form of spray device and overflow connections;

Fig. 7 is a view similar to Figs. 2 and 6 but showing another modification; and

Fig. 8 is a side elevational view, partly in section, showing modified means for driving the spray devices.

Referring to the figures, I have shown apparatus for scrubbing, cleaning and cooling gases which includes a tower 1, preferably circular in cross section and of considerable height, the dimensions of the tower being, of course, dependent upon the amount of gas to be treated. The tower may conveniently be constructed of sheet metal side walls 2 and is provided with channels 3 which extend across the tower, at intervals, and are carried by the outer walls 2 of the tower. These channels will presently be described in more detail.

Within the tower I provide a plurality of gas-treating compartments 4 spaced vertically apart from each other, or superimposed upon each other. Each compartment 4 is provided with a bottom wall 5 which extends across the tower, from side to side, but is spaced apart from certain portions of the walls of the tower to provide passages 6 through which gas may pass. Each cross wall includes a centrally disposed pan 7 adapted to retain liquid, and from the edges of which the remaining parts 8 of the cross wall slope upwardly towards the side walls of the tower so that water falling thereon will flow into the pan. Preferably, this pan is non-circular and may assume the shape of a diamond, or other figure which is not substantially circular, as desired. A circular, conically shaped ring 9 is supported from the side walls of the tower in each gas treating compartment above the bottom wall 5 of the compartment and extends inwardly from the walls of the tower a distance sufficient to discharge water falling thereon onto the bottom wall of the compartment. This ring also acts as a baffle to gases passing upwardly, by way of passages 6, through the tower 1 and deflects the gases inwardly in each compartment where they may be suitably treated.

Means is provided within each compartment for forming spray from liquid in the pan in a manner to act upon gases passing through the compartment and remove foreign

materials and heat therefrom. Such means, as illustrated, comprises a pump composed of a plurality of nested cones 10 mounted on a shaft 11 which is supported or suspended on antifriction bearings 12 preferably disposed adjacent to the said pump and here shown as being disposed above the liquid in the compartment and also above the cones. The top wall 13 of each compartment extends across the tower between the side walls 2 thereof, but is spaced apart therefrom at certain places to provide passages 14 for gas to flow from one compartment 4 to the next higher compartment. In the top wall of each compartment 4 is provided a centrally disposed opening 15 through which the pump may be removed. The cover 16 for this opening may conveniently carry the antifriction bearings 12 which support the pump and may suspend the pump in its compartment.

Between the top wall 13 of one gas-treating compartment 4 and the bottom wall 5 of the next higher compartment, I provide work passages 17 which preferably extend through the tower and are open at either or both ends, as may be desired. As shown in Fig. 1 these work passages are arranged each at right angles to the adjacent passages, but as shown in Fig. 8 these passages may be parallel to each other in a vertical plane. Each passage 17 is formed by the top wall 13 of one gas treating compartment, the bottom wall 5 of the next higher compartment and by side walls 18 which extend across the tower from one side wall to or toward the other, and are secured to the top and bottom walls of the passage. Gas within the tower thus cannot escape into the work passages 17 except when the cover 16 of the opening 15 is removed.

The channel members 3, previously referred to, serve not only to support the bottom wall 5 of each gas-treating compartment, but also serve as tracks for a suitable crane 19 or similar device by means of which the pump and its associated parts may be removed from its compartment. As shown in Fig. 1 I have provided in each work passage a motor 20 which is connected by suitable couplings 21, gearing 22 keys and keyways or the like to the pump of the compartment therebeneath. By such an arrangement I am able to regulate and vary the speed of each pump as desired to obtain the best results, since I have found that the speeds of pumps in the compartments which remove foreign material and solids from the gases may advantageously be different from the speeds of pumps in compartments where only final cooling of the gases takes place. Furthermore, with driving means independent of the other pumps or spray forming devices, any given pump or device may be repaired and adjusted without stopping the other pumps and may be removed and replaced without inter-

rupting the operation of the tower for more than a very few minutes.

Another means of accomplishing substantially the same results is shown in Fig. 8 where a main drive shaft 23 is mounted outside of the tower and provided opposite each of the work passages 17 with a suitable shaft 24 and pulleys 25 which are connected by belts 26 or other suitable means to suitable shafts 27 and gearing so that each pump may be driven by the common shaft 23 and so that the speed of each pump may be varied independently of the other pumps and the rotation of any pump may be discontinued without affecting the other pumps or the operation of the tower.

It will be evident from the drawings and the foregoing description that I have provided bearings for supporting each pump and also have provided means for rotating the pump. In Fig. 2 the bearing means for supporting pump 10 includes the shaft 11, cover 16 and bearing 12 which serve to prevent longitudinal or transverse movement of the pump. The means for rotating the pump includes the keys and keyways, or the like, of Fig. 2 or Fig. 8 with one or more power devices, such as motor 20 or shaft 23, or their equivalents.

Means is provided for withdrawing liquid from each gas-treating compartment. Since these means for each of the upper compartments are all substantially alike, only one will be described. This means comprises an elongated casting 28 having an outlet opening 29 disposed centrally beneath the pump and preferably within the inner cone 10 thereof. A ring 30 movably and adjustably mounted within this opening 29 serves as a

weir or valve and controls the flow of liquid through the outlet opening. It is actuated by a hand wheel 30^a and screw 30^b, the latter being disposed in the work passage 17 there-

beneath and outside the casing. At either end of the casting 28 gas vents 31 are provided on substantially the same level as the top edge of the bottom wall 5 of the compartment

4, as clearly shown in Fig. 2. Liquid flowing into the casting through the central opening 29 is discharged through suitable outlet openings 32 at either end of the casting and conducted to the compartment next below.

In Fig. 6 liquid passing through these outlet openings 32 flows through pipes 33 which lead into the work passage 17 therebeneath and empty into a shallow saucer 34 formed on the top of the inner cone 10 of each pump. An alternative arrangement is shown in the other figures where the liquid discharged

from the casting is permitted to flow down the side walls 18 of the work passage 17 and is then deflected by the ring 9 into the pan therebeneath. The means for withdrawing liquid from the bottom compartment differs somewhat from the means employed for that pur-

pose in the upper compartments. Preferably it consists of a clean-out pipe 37 having a control valve 37^a and an emptying valve 37^b, and may lead to thickening apparatus or settling tank 38. Preferably it also includes an overflow pipe 39 which leads to device 38. 70

In Fig. 7 I have shown means for confining within relatively narrow limits the rotation of liquid in the pan 7, which is caused by rotation of the cone pump. This means consists of an annular member or ring 35 carried by the casting and suspended with its top edge substantially flush with liquid in the pan, when the liquid is at rest. This ring 35 is narrow so that it does not extend to the bottom of the pan and is preferably only slightly greater in diameter than the outside cone 10, so that when assembled with the pump it will lie close to the outside of the pump and thereby limit rotation of the liquid 80 in the pan to a small area. As shown in this figure, the surface of the liquid in the pan tends to assume a parabolic configuration, as indicated at 36, when the pump is rotated. With the ring 35 positioned as described, the liquid within the ring will flow over the top of the ring, the existence and extent of such overflow being determined by the adjustable weir 29. 90

The top group of compartments is indicated by the bracket *a* on Fig. 1 and consists of four stages, while the bottom group is indicated by bracket *b* in the same figure and consists of two stages. It will be understood that more stages may be employed, if desired, 100 and more or less compartments in each group may also be used. The top group is referred to herein as the "gas-cooling group" in which gases passing therethrough are given their final cooling and some slight cleaning, while the bottom group of stages is referred to as the "gas-scrubbing group" in which practically all of the foreign materials including solids are removed from the gases and in which the gases are given their initial cooling 110 amounting to a large proportion of the entire cooling thereof.

In Fig. 1, I have shown means including pipe 40 and pump 41 for withdrawing liquid from the bottom stage or compartment of the top group of stages, passing it through means 42 for cooling the liquid and returning it by means or pipe 43 to an upper stage or compartment.

In Fig. 1, I have also shown means including pipes 37 and 39, or either of them, and pipes 46 with pump 47 for withdrawing liquid from the bottom gas-treating compartment of the tower 1, passing it through thickening devices 38 and returning it to the top gas 125 scrubbing compartment.

I have also shown means including pipe 44 and valve 45 for diverting to the cooler 42 some or all of the water flowing from pump 47 in pipe 46. 130

In operating the apparatus described, gas at a temperature of perhaps 400° F. and carrying foreign materials including solids is led into the bottom of the tower 1, as at 48, and then passes upwardly through the several gas treating compartments 4 where it is first initially cooled and deprived of a major part of its heat and all but small amounts of its foreign materials and solids and later is finally cooled and more completely cleaned until it issues from the top of the tower at a temperature of from 70° F. to 80° F. and with a relatively small content of foreign materials and solids. As the gas enters and passes through the bottom group of compartments, the pumps in these compartments are rotated and convert liquid in the pans into spray which serves to remove foreign materials and solids from the gases and carry them to the liquid in the pan. The liquid is continuously recirculated in this manner and soon after starting contains a relatively large amount of accumulated foreign material. This liquid is withdrawn from the bottom compartment, preferably continuously, and passed through a settling tank or suitable thickening apparatus 38 where the liquid is separated from most of, but not all, its foreign materials and then returned to the top compartment of the bottom or gas-scrubbing group of compartments or alternatively, part of or all of the water may be passed through the cooler 42 and then returned to the compartments by way of pipe 43. As much as 100 to 200 grains of solids per gallon of liquid may remain in the liquid, which is thus returned to the gas-scrubbing group of stages.

In the top or gas-cooling group of stages liquid is similarly converted into spray form and continuously recirculated by the pumps therein and the gases are deprived of practically all of their remaining content of foreign materials and cooled through the last few degrees and to about 70° F. or 80° F. The liquid from the bottom compartment of the top or gas-cooling group of compartments is circulated through cooling tower 42 where it is cooled and then returned to the top compartment of the group, together with sufficient fresh liquid to make up for the liquid evaporated by the hot gases and lost in other ways. In this manner the amount of liquid in the top group of compartments is maintained substantially constant. Liquid is withdrawn from the bottom stage of the top group and conducted to the top stage of the bottom group to maintain the amount of liquid in the gas-scrubbing group of compartments substantially constant. By reason of the addition of fresh liquid, which preferably is made continuously, the liquid is constantly renewed in all the stages and the content of solid materials in the liquid thus is easily maintained below suitable maximum amounts.

Preferably, the liquid is withdrawn from the bottom group of compartments at such a rate that the solids are removed from the tower at approximately the same rate as they are separated from the gases by the liquid. Thus the liquid in the bottom group of compartments contains at all times an approximately uniform amount of solids.

It will be understood that although I return liquid having a substantial content of solid material to the gas-cleaning group of compartments, it still retains its gas-cleaning capacity since this does not depend upon the amount of solids in the liquid but rather depends upon the temperature of the liquid. It appears that warmer liquids remove solids from gases more completely and in turn give up the solids more quickly than colder liquids.

Although I employ comparatively small amounts of fresh liquid and return much heated liquid to the tower as contrasted with various prior art processes where the liquid is discarded after being withdrawn from the tower, I am able to cool the gases to substantially the same temperature as has been common practice heretofore. Although the gases entering the bottom group of compartments may have an average temperature of about 400° F. and at times higher, I have found that the temperature of water circulated as described in the bottom group of compartments will rise only until a balance is reached, which may be stated as being that temperature at which the number of heat units given off by the hot gases entering the tower is equal to the heat units absorbed in evaporating sufficient water to saturate or nearly saturate the gas with water vapor. With the incoming gas at about 400° F. and with the usual amount of water vapor, this temperature will be in the neighborhood of about 135° F. With the incoming gases at higher temperatures and with an amount of water vapor higher than normal, this temperature will be somewhat elevated but as the capacity for water vapor increases very rapidly at and above this temperature, the temperature of the water will not rise very much above these figures.

The details of structure and description appearing hereinabove have been given by way of illustration only and not for the purpose of limiting the invention thereto. Various changes may be made without departing from the spirit of my invention, the scope of which is defined in what is claimed.

What is claimed is:

1. The method of treating gases which comprises recirculating gas-cooling liquid in spray form in a space occupied by a heated gas, circulating liquid from the said space through means for removing accumulated heat therefrom and back to the said space, and circulating liquor from the said space through means for removing accumulated

foreign material therefrom, and back to the said space, and adding fresh liquid to maintain the amount thereof substantially constant.

5. 2. The method of treating gases which comprises recirculating gas-cooling liquid in spray form in a space occupied by a heated gas, circulating liquid from the said space through means for removing accumulated 10 heat therefrom and back to the said space, recirculating gas-cleaning liquid in spray form in another space occupied by a gas carrying foreign material, circulating liquid from the last said space through means for 15 removing accumulated foreign material therefrom, and back to the last said space, adding fresh liquid to the gas-cooling liquid to maintain the amount thereof substantially constant, and withdrawing heated liquid 20 from the gas-cooling space and adding it to the gas-cleaning liquid to maintain the amount of the latter liquid substantially constant.

3. Apparatus for treating gases comprising means for removing heat from gases including means for circulating liquid in spray form in contact with gases to be cooled, means for cooling the said liquid heated by the gases, means for circulating liquid from the first 30 said means through the second said means and back into the first said means, means for removing foreign material from gases including means for recirculating liquid in spray form in contact with gases to be 35 cleaned, liquid-cleaning means for removing foreign material from said gas-cleaning liquid, means for circulating liquid from the gas-cleaning means, through the liquid-cleaning means and back to the said gas-cleaning 40 means and means connecting the gas-cooling means and gas-cleaning means for conducting liquid from the former means to the latter.

4. Apparatus for treating gases which includes a tower having gas treating compartments, a liquid spraying and recirculating device suspended within each gas compartment, means disposed outside of each gas compartment for supporting the said device, 50 and means to actuate each device independently of the remaining devices.

5. Apparatus for treating gases which includes a tower having vertically spaced gas-treating compartments and having work passages extending transversely of the tower between adjacent gas-treating compartments, and gas passages disposed within the tower and at the sides of the work passages for interconnecting adjacent compartments for the 55 passage of gas successively through a plurality of compartments.

6. Apparatus for treating gases which comprises a tower having a plurality of interconnected gas-treating compartments spaced vertically apart from each other, and

having also a plurality of work passages extending transversely of the tower between the gas-treating compartments, a liquid spray forming device within each compartment and accessible from the adjacent work passage 70 and means for actuating the devices.

7. Apparatus for treating gases which comprises a tower having a plurality of interconnected gas-treating compartments spaced vertically apart from each other, and having also a plurality of work passages extending transversely of the tower between the gas compartments, a liquid spray forming device within each compartment, means in the work passage above each said device for suspending the same within its compartment, and means for actuating the devices. 75

8. Apparatus for treating gases which comprises a tower having a plurality of interconnected gas-treating compartments spaced vertically apart from each other, and having also a plurality of work passages extending transversely of the tower between the gas compartments, each work passage having an opening through the floor thereof into the 80 gas-compartment therebeneath, a spray device removable through each said opening, means in the work passage for suspending the device within the compartment therebeneath and means for actuating each device independently of the other devices. 85

9. Apparatus for treating gases which comprises a tower having a plurality of interconnected gas-treating compartments spaced vertically apart from each other, and having also a plurality of work passages extending transversely of the tower between the gas compartments, each work passage having an opening through the floor thereof into the 90 gas-treating compartment therebeneath, a spray device removable through each said opening, means in the work passage for suspending the device within the compartment therebeneath and means for actuating each device independently of the other devices. 95

10. Apparatus for treating gases which comprises a tower having a plurality of interconnected gas-treating compartments spaced vertically apart from each other, and having also a plurality of work passages extending transversely of the tower between the gas compartments, each work passage having an opening through the floor thereof into the 100 gas-treating compartment therebeneath, a spray device removable through each said opening, means in the work passage for suspending the device within the compartment therebeneath and means in the work passages for actuating each device independently of the other devices. 105

11. Apparatus for treating gases which comprises a tower provided with a plurality of separate gas-treating compartments joined together by gas passages, each compartment including a non-circular, liquid retaining pan, a cone pump projecting to below the top 115 120 125 130

- edge of the said pan and means for controlling the level of liquid in the said pan, the said means including an elongated, hollow member having an opening in its lower portion disposed to discharge liquid through an opening in the lower portion of the pan and having a central inlet opening at its top disposed centrally beneath the said pump. 17. Apparatus for treating gases which includes a tower having gas treating compartments, work passages extending transversely of the tower between adjacent gas compartments, independent liquid spray-forming units supported in the passages and each extending into an adjacent gas compartment, and means for actuating the devices independently of each other. 70
12. Apparatus for treating gases which comprises a tower through which gases may pass and having a plurality of separate gas-treating compartments within the tower, each compartment having a liquid retaining pan, a spray forming device suspended in each pan, and an adjustable weir disposed centrally below the said device for controlling the level of liquid in the said pan. 18. Apparatus for treating gases which includes a tower having gas treating compartments, work passages extending transversely of the tower between adjacent gas compartments, and independent spray-forming units supported from the passages, each unit comprising a spray-forming device extending into and disposed to spray liquid in a gas compartment, and actuating means for each device disposed in the adjacent work passage. 75
13. Apparatus for treating gases which comprises a tower through which gases may pass and provided with a plurality of separate gas-treating compartments joined together by gas passages, each compartment including a liquid retaining pan, a cone pump projecting to below the top edge of the said pan, and means for controlling the level of liquid in the said pan, the said means comprising an elongated hollow member having a central inlet opening in its top and outlet openings in its bottom, communicating with the space below the pan through openings in the bottom of the pan, the inlet opening being disposed centrally beneath the said pump, and adjustable means disposed within the said inlet opening for varying the level of liquid in the said pan. 19. Apparatus for treating gases which includes a tower having gas treating compartments, work passages extending transversely of the tower between adjacent gas compartments, and independent, spray-forming units supported from the passages, each unit comprising a spray-forming device extending into a gas compartment, and means disposed in the work passages for supporting the devices independently of each other. 80
14. Apparatus for treating gases which comprises a tower through which gases may pass and provided with gas-treating compartments, each compartment having a liquid retaining pan provided with a central liquid outlet, a cone pump suspended in the pan centrally above the said outlet, and an annular ring substantially submerged in liquid in the pan and surrounding the said pump, the ring being slightly greater in diameter than the pump and of less depth than the depth of the pan. 20. Apparatus for treating gases which includes a tower having gas treating compartments, work passages extending transversely of the tower between adjacent gas compartments, and independent spray-forming units in the compartments, each unit being supported in a work passage independently of each other and actuated independently of each other. 90
15. A method of treating gases which comprises spraying, collecting and respaying liquid within a chamber occupied by heated gases containing solid particles, and simultaneously circulating parts of said liquid through means for removing accumulated solids and accumulated heat units from the said liquid and returning the said liquid to the said chamber. 21. The method of treating gases which comprises spraying, collecting and respaying liquid within a given chamber in contact with heated gases previously freed from a part of the foreign material with which they were laden, thereafter withdrawing from the said chamber the said sprayed, collected and respayed liquid, passing the liquid through means for removing accumulated heat therefrom and back to the said chamber, and subsequently removing from the said liquid foreign materials which have accumulated therein. 100
16. Apparatus for treating gases which comprises a tower through which gases may flow and having a plurality of work passages extending transversely of the tower, each work passage having an opening therefrom into the interior of said tower, a spray forming device associated with and removable through the said opening, and means in each work passage for supporting said spray forming device within the tower. 110
17. The method of treating gases which comprises spraying, collecting and respaying cleaning liquid within a chamber in contact with heated gases laden with foreign materials, then withdrawing the said liquid from the chamber and passing it through means to remove accumulated foreign materials therefrom and back to said chamber, and passing the thus cleaned but still partly heated gases into a second chamber, then spraying, collecting and respaying cooling liquid in said second chamber in contact with 120
18. The method of treating gases which comprises spraying, collecting and respaying liquid within a chamber in contact with heated gases laden with foreign materials, then withdrawing the said liquid from the chamber and passing it through means to remove accumulated foreign materials therefrom and back to said chamber, and passing the thus cleaned but still partly heated gases into a second chamber, then spraying, collecting and respaying cooling liquid in said second chamber in contact with 125

said cleaned gases and withdrawing sprayed collected and resprayed liquid from the said second chamber and passing it through means to remove accumulated heat therefrom and back to said second chamber.

5 23. Apparatus for treating gases which comprises a tower having a plurality of vertically arranged interconnected gas treating compartments, movable spray forming devices in the compartments, work passages each extending transversely of the tower between adjacent compartments in proximity to the devices therein and having a normally closed opening for access to the device in 10 one of the adjacent compartments, and means for actuating the spray forming devices.

15 24. Apparatus for treating gases which comprises a tower having a plurality of vertically arranged interconnected gas treating 20 compartments, rotary spray forming device in the compartments, bearing means operatively associated with and disposed adjacent to each device, work passages each extending transversely of the tower between adjacent 25 compartments and in proximity to the device and bearing means in one of the adjacent compartments, and having a normally closed opening for access to the said bearing means, and means for actuating the spray forming 30 devices.

35 25. Apparatus for treating gases which comprises a tower having a plurality of vertically arranged interconnected gas treating compartments, a plurality of rotatable spray forming devices in the compartments, bearing means operatively associated with and disposed adjacent to the said devices, work 40 passages each extending transversely of the tower between adjacent compartments and in proximity to the devices therein and their bearing means, the said work passages having means for permitting access therefrom to the adjacent spray forming devices and their bearing means, and means for rotating the 45 said devices.

50 26. Apparatus for treating gases which comprises a tower having a plurality of vertically arranged interconnected gas treating compartments, a plurality of rotatable spray forming pumps in the compartments, individual bearing means each operatively associated with one of the said pumps and disposed adjacent thereto, a plurality of work 55 passages each extending transversely of the tower between adjacent compartments and in proximity to the adjacent pumps and bearing means, means in the work passages for permitting access to the bearing means of the pump adjacent thereto, and a power shaft 60 operatively associated with the pumps to rotate the same.

In testimony whereof I hereunto affix my signature this 26th day of June, 1925.

ARTHUR G. McKEE.
